UNITED STATES PATENT OFFICE.

JAMES JOHNSON, OF BOLTON, ENGLAND.

CONSTRUCTION OF RAIN-WATER DOWN-SPOUTS.

SPECIFICATION forming part of Letters Patent No. 453,485, dated June 2, 1891.

Application filed March 12, 1891. Serial No. 384,815. (No model.) Patented in England February 5, 1889, No. 2,023.

To all whom it may concern:

Be it known that I, JAMES JOHNSON, coal merchant, of Clive Street, Bolton, in the county of Lancaster, England, have invented new and useful Improvements in the Construction of Rain-Water Down-Spouts, of which the following is a specification, and for which I have obtained a patent in Great Britain, No. 2,023, dated February 5, 1889.

10 This invention relates to improvements in the construction of rain-water down-spouts, and has for its object that of dispensing with the old and objectionable system of drilling and plugging walls to fix the same; also, to 15 facilitate removal in case of painting and repairs.

Figure 1 is a sectional elevation of my improved rain-water down-spouts. Fig. 2 is a front elevation of same, and Fig. 3 is a plan 20 of socket. A A are sockets provided with the spigots B and ears C. The ears C are provided with the holes D to receive the ordinary nails F for securing the sockets to the wall. The spigot B is of sufficient length to 25 allow of the nails F being driven into a joint to dispense with the system of drilling and plugging walls to fix the same. After the 30 sockets A A have been fixed in position they are connected by the straight pipe E, the upper end being placed on the outside of the spigot B and the bottom end on the projections G, formed in the sockets A. The 35 projections G are constructed, as shown in Fig. 3, to allow water that may dribble down the outside of the pipe E to flow into its supporting-socket and down the remaining spouts to the drain. The length of the spigot B allows of 40 the pipe E being slid thereon to place it in position without disturbing the sockets. The straight pipes E can be cast in the usual manner or made from sheet or galvanized iron and riveted or otherwise. Owing to the pipes 45 E being made separate from the sockets A they can be turned round by hand to allow of their being painted uniformly on the outside, an advantage entirely unknown hitherto.

To remove the down-spouts from the wall to prevent the latter being damaged by water in case of leakage, the ears C are cast on the 50 sockets A, as shown in Fig. 3, or as in Fig. 4,

wherein the loose pieces H are placed behind the ears C and secured by the nails F. The outside of the pipes E can be of any desired ornamental design, with sockets to correspond.

Fig. 6 is a part front elevation of my improved down-spouts when made oblong, and Fig. 7 is a sectional plan through line A² B² in Fig. 6. In case the pipes E and spigots B are made square or oblong it will be necessary to remove the pipes E from the spigots B and sockets A when desired, for the purpose of painting the back side or repairs.

Fig. 8 is a part front elevation of my improved down-spouts, wherein the outside of the pipes E are octagonal in form. Fig. 9 is a sectional plan through line C² D² in Fig. 8. Fig. 10 is a part front elevation of my improved down-spouts, wherein the outsides of the pipes E are square. Fig. 11 is a sectional plan through line E² F² in Fig. 10, and Fig. 12 is a sectional plan through line G² H² in Fig. 10. To enable the pipes E, with square, octagonal, or other polygonal outside forms to be turned round by hand when in position for the purpose of painting and repairs, the spigots B are circular, as in Figs. 1, 2, 10, and 11, the internal diameter of the sockets A being larger than the distance across the angles of the pipes E. The sockets A are in all cases provided with the projections G, for the purpose before mentioned. To prevent the pipe E that is within reach being lifted out or tampered with by mischievous persons, the clip M (shown in Figs. 1 and 5) is fixed between the under side of the socket A and the top side of the pipe E.

Having now particularly described and ascertained the nature of my invention and in what manner the same is to be performed, I declare that what I claim is—

The combination of the pipes E and the sockets A with the spigots B and projections G, substantially as and for the purpose hereinbefore set forth.

In testimony whereof I affix my signature in presence of two witnesses.

JAMES JOHNSON.
